UNITED STATES PATENT OFFICE.

SYLVESTER GEORGE STEVENS, OF DULUTH, MINNESOTA.

LIFE-SAVING APPARATUS FOR SHIPS.

No. 829,179.

Specification of Letters Patent. Patented Aug. 21, 1906.

Application filed January 16, 1903. Serial No. 296,520.

To all whom it may concern:

Be it known that I, SYLVESTER GEORGE STEVENS, a citizen of the United States, residing at Duluth, in the county of St. Louis and State of Minnesota, have invented certain new and useful Improvements in Life-Saving Apparatus for Ships, of which the following is a specification, reference being had therein to the accompanying drawings.

10 My invention relates to improvements in life-saving apparatus for ships, and pertains particularly to an apparatus carried by the ship.

15 The object of my invention is to provide a life-saving apparatus of this character which is made as a permanent fixture of the ship and extends from the bow to the stern of the vessel and adapted to convey persons from one end of the ship to the other end.

20 In ships of great length the deck-houses for passengers are at each end, and when a vessel strikes the bottom or grounds it invariably happens that the vessel breaks in two in the middle or, when made of steel, 25 buckles, leaving practically two isolated and independent wrecks, neither end of the ship being able to assist the other in the least on account of the lack of communication.

25 In a device of the character herein described a life-line is kept intact from one end of the vessel to the other, and the end of the vessel striking bottom is the end of the vessel nearest shore and from which the persons thereon are usually saved, while those on the 35 opposite end are lost, while by having a life-line intact from one end of the vessel to the other the persons can be conveyed from the end away from the shore to the end nearest shore, and thus allow of the more 40 saving of all persons on board.

In the accompanying drawings, Figure 1 is a side elevation of a ship, showing my life-line applied and which is at all times, while the vessel is at sea, kept intact. Fig. 2 is an 45 enlarged side elevation showing the deck-houses at the ends of the ship and showing an enlarged view of the life-saving apparatus. Fig. 3 is a side elevation of a ship after it has 50 grounded and broken in two and showing the line intact and adapted to convey persons from one end to the other across the broken central portion of the ship.

Referring now to the drawings, 1 represents the ship which, as shown, is of an elongated

5 from four to six hundred feet and provided at its forward end with the deck-housing 2 and at the rear end with the deck-housing 3 and below which are usually arranged the 10 cabins for the passengers in freight-steamers of this character, and when a wreck occurs it is often impossible for the passengers of one cabin to reach the other cabin and, as before stated, the ship forms two isolated wrecks. The ship above the deck-housings 2 and 3 is 15 provided with the usual spars 4 and 5, which carry the usual rigging. The rear deck-housing 3 is provided with a short auxiliary 20 spar or post 6, located in any convenient and accessible place, preferably in the center of 25 the ship and at the forward end of the deck-housing 3, so that the same will be in alignment with the forward spar 4. The said 30 auxiliary spar 6 at its upper end is provided 35 end with the single sheave-block 8. The 40 spar 4 at the forward end of the vessel is provided 45 with a double sheave-block 7 and its lower 50 spar 4 at the forward end of the vessel is provided 55 with a double sheave-block 9, the same 60 distance from the deck as the block 7, so that 65 the cable will be normally held in a horizontal 70 position. The said spar 4 adjacent its 75 lower end is also provided with a single 80 sheave-block 10. The cable 11, which, as 85 shown, is of an endless construction, passes 90 over the double sheave-blocks 7 and 9 and 95 around the single sheave-blocks 8 and 10, and thus arranging at each end the substantial 100 vertical portions 12 and 13 at each end between the single and double sheave-blocks for convenience in operating the same by 105 persons upon the deck-houses, as well as by the person being conveyed across from one end of the ship to the other. The said cable 11 between the double blocks 7 and 9 is provided 110 with a loop or breech buoy 13', which 115 is attached to the cable in case of a wreck or may be permanently secured to the line so as to always be in readiness in case of an 120 accident. It is understood that the cable 11 is always in its operative position over the 125 blocks to be ready at a moment's notice in 130 case of an accident.

The auxiliary spar 6 may be and is preferably provided with cables 14, which pass over blocks 15, carried by the upper end of the housing and by means of which the spar may be tightened to assist in tightening or loosening the cable 11 to prevent the cable

from being too low as to interfere with the deck of the ship in its travel from end to end of the vessel. These cables also serve as additional means for securing the apparatus to the vessel and prevent it being washed overboard in the event of a severe wreck.

Instead of having the double blocks 7 and 9 the same could be single, and the cable 11 could pass over the same and around the single blocks 8 and 10 and pass completely around them, as indicated in dotted lines, Fig. 3, the loops or breech-buoys being fastened to the upper line, as the weight of the person on it would tend to bring the two lines closer to each other, which would allow the person to aid in his travel along the same.

While I have shown and described these two forms of carrying out my invention, it will be understood that I do not care to limit myself to either form, as the same may be carried out in numerous other ways without departing from the spirit and scope of my invention.

In vessels of this character to which my device is usually applied the smoke-stack 16 is at the rear end above the deck-housing 3, and, if desired the auxiliary spar 6 can be dispensed with and the blocks 7 and 8 be carried by the smoke-stack 16 and the cable 11, passing over said blocks.

Having thus described my invention, what I claim, and desire to secure by Letters Patent, is—

1. The combination with a vessel having superstructures above the main deck thereof, of a laterally-suspended traveling device communicating between said superstructures.

2. The combination with a vessel, of an uninterrupted fore-and-aft life line or lines suspended centrally above the main deck thereof and communicating with the extreme forward and after deck houses, means for retaining said line or lines in an accessible position from the deck-houses and having holdfast means attached to said life-line for the purpose described.

3. The combination with a vessel, of a fore-and-aft life line or lines suspended centrally above the main deck thereof with means for retaining said line or lines in a taut and accessible position from the deck-houses, and loops or buoys attached to said line or lines for the purpose described.

4. The combination with a vessel, of a fore-and-aft life-line supported centrally above the main deck thereof and extending substantially the full length of the same with means for retaining said line in a taut and accessible position from the two ends of the vessel for the reception of life-buoys or holdfast means for transferring persons from one end of the vessel to the other.

5. The combination with a vessel, having the usual spars forward and aft, of blocks carried by the spars and an endless cable

passing over the blocks from spar to spar, said cable being located in an accessible position for life-saving purposes from both ends of the vessel.

6. The combination with a vessel having the usual spars fore and aft, of blocks carried by the spars, an endless cable passing over the blocks from spar to spar, and a loop or breech-buoy carried by the cable intermediate the blocks.

7. The combination with a vessel having the usual spars fore and aft, of an auxiliary spar in front of the aft spar, means for adjusting said spar, double blocks carried by the upper end of the auxiliary spar, and the forward spar, single blocks carried by the lower end of the spars, an endless cable passing over the double blocks and around the single blocks, and a loop or breech-buoy carried by the cable between the double blocks.

8. The combination with a vessel having the usual spars fore and aft, single blocks carried by the spars, an endless cable passing around said blocks, and a loop or breech-buoy carried by the cable intermediate the upper blocks.

9. The combination with a steam vessel having the usual spar forward and smoke-stack aft, sheave-blocks carried by said spar and stack, an endless line passing around said blocks, and a loop or breech-buoy carried by the line intermediate the spar and stack.

10. The combination with a vessel having the usual spars fore and aft; of an auxiliary spar in front of the aft spar, blocks carried by the auxiliary and forward spars, and an endless cable passing around the blocks, and a loop or breech-buoy carried by the cable between the blocks.

11. The combination with a vessel having superstructures above the main deck thereof, of a suspended traveling device communicating between said superstructures.

12. The combination with a vessel having a plurality of deck-houses, of a laterally-operative transportation means communicating between said deck-houses and extending centrally and lengthwise of the ship for life-saving purposes.

13. The combination with a vessel having a plurality of deck-houses, of a laterally-operative life-saving means suspended between said deck-houses while at sea for transportation purposes in case of emergency.

14. The combination with a vessel having a plurality of superstructures above the main deck thereof, of a laterally-operative life-saving means above said deck suspended from and connecting said superstructures.

15. The combination with a vessel having the usual spars forward and aft, of an auxiliary spar in front of the after spar, blocks carried by the auxiliary spar and forward spar, and an endless cable passing around the

blocks, and a loop or breech-buoy carried by the cable between the blocks.

16. The combination with a sea-going vessel, of vertically-extending supports from both ends of the main deck thereof and an operative life line or lines extending lengthwise of the vessel and suspended from said supports considerably above the main deck

of the vessel, said line or lines carrying holdfast transportation means. 10

In testimony whereof I affix my signature in presence of two witnesses.

SYLVESTER GEORGE STEVENS.
